UNITED STATES PATENT OFFICE.

CARL E. DRANGE, OF PLAINFIELD, NEW JERSEY, ASSIGNOR TO ISABELLA SCOTT AND DAVID J. SCOTT, EXECUTORS OF THE ESTATE OF WALTER SCOTT, DECEASED, DOING BUSINESS UNDER WALTER SCOTT & COMPANY, OF PLAINFIELD, NEW JERSEY.

WEB-REPLENISHING MECHANISM.

Application filed October 21, 1925. Serial No. 63,817.

This invention relates generally to a method and means to be used in printing, folding or other web-pulling machines for uninterruptedly feeding a web of flexible material while changing from an employed roll to a replenishing roll.

This invention embodies the method and means disclosed in application Ser. No. 44,506, filed July 18, 1925, in which a surplus 10 is accumulated in an employed web to slow down or stop a portion of the employed web so that another web may be attached thereto and is, therefore, subsidiary to said application.

15 The main object and feature of this invention is to provide a method and means whereby the replenishing roll may be started up before the replenishing web is attached to the employed web, a portion of the replenishing 20 web nevertheless standing still, or approximately so, at the time the two webs are changed.

Other features of the invention will appear as the specification proceeds.

25 In the accompanying drawings the invention is disclosed in several concrete and preferred forms in which:

Fig. 1 is a view in side elevation of a machine embodying the invention:

30 Fig. 2 is an end view, partly in section, in the plane of line 2—2 of Fig. 1:

Fig. 3 is a view similar to Fig. 1, but in section in the plane of line 3—3 of Fig. 2, showing the device at the beginning of its 35 cycle of movements:

Fig. 4 is a view, similar to Fig. 3, with the parts in the position they occupy during the period of inaction of the device:

Fig. 5 is an enlarged view of the lower 40 part of Fig. 3 with the parts shown in the position they occupy at the time the old web is severed: and

Fig. 6 is a diagrammatic view showing a modified form of the invention.

45 104 indicates a web surplus accumulating and dissipating device, here taking the form of a carriage that reciprocates in horizontal guides 150 and carries at its end a roll 105, which, when moved to the extreme right-hand position (Figs. 3 or 4), accumulates a surplus in the web between stationary rolls

106 and 107. 102 indicates an auxiliary web surplus accumulating and dissipating device, here taking the form of a carriage that reciprocates in vertical guides 151 and carries two rolls 103 and 103^a, which, when moved in a downward direction (Figs. 3, 4 and 5), accumulates a surplus in both the employed and the replenishing webs between rolls 100, 101 and 103 and 103^a. The two devices act in opposition to each other; that is, when one device is accumulating a surplus, the other is dissipating it, and vice versa. Any suitable means may be used to actuate these devices but, in the present instance, 152 indicates a shaft suitably driven from the web-pulling machine indicated diagrammatically at 153. 154 indicates another shaft having a one-revolution clutch 155 which, when thrown in, couples sprocket 156 to shaft 155. Sprocket 156 is driven from shaft 152 by means of sprocket 157 and chain 158. 159 is a shaft driven by means of bevel gears 160 from shaft 154; and 159 carries a crank arm 161 and a connection 162 is interposed between the crank arm and carriage 104. Shaft 159 also carries a sprocket 163 which drives sprocket 164 by means of chain 165; and sprocket 164 is fast on shaft 166 that carries a crank arm 167; and a connection 168 is interposed between the crank arm and carriage 102.

1 is a web roll from which leads web 2 passing over spring roller 3 and roller 4 beneath tension roller 5 to roll 100 and thence around roll 103 up through the machine around rolls 107, 105 and 106 and thence to the web-pulling machine. For the purpose of this explanation and as an example of how the machine may operate, roll 1 may be considered the employed roll and web 2 the employed web. 38 indicates a second web roll, here the replenishing roll from which leads replenishing web 37 passing over spring roller 39, roller 40, tension roller 41, roll 101, roll 103^a and up through the machine to gripper or clamp 123. There is a similar gripper or clamp 122 on the other side of the webs to be used when web 2 is the replenishing web and 37 is the employed web. 108 and 109 indicate two web-attaching members coming on opposite sides of the two webs and arranged face to

face, said members here being shown as two arms loosely mounted in centers 100 and 101 and normally held in an upright position by means of springs 169 in such way that these members do not press the webs together. Clamps 122 and 123 are conveniently carried by members 108 and 109. Rolls 5 and 41 and 3 and 39 are part of what is known as the Jones tension device disclosed in Patent No. 1,395,830 of November 1, 1921, that automatically actuate brake mechanism in a manner well understood in response to variations in the tension of the web; but it is to be distinctly understood that the employment of this automatic tension device is optional and does not form a necessary part of my invention. Mounted on carriage 102 are rolls 114 and 115; and carried by members 108 and 109 are cams 116 and 117 and these cams and rolls cooperate to move members 108 and 109 toward and away from each other when carriage 102 reciprocates. If desired, members 108 and 109 may be swung down out of the way, as indicated in dotted lines in Fig. 3, and have, for that purpose, handles 170; and 171 indicate latches for holding said members in their lowered position. Suitable severing devices are provided consisting of severing members 120 and 121 pivotally supported at 172 and these severing devices are actuated by cams 173 acting against rolls 174 unless prevented from so doing by removable pins 175 in which case springs 176 take up the motion of the cams and the severing members are not actuated. Means are preferably provided for setting the device automatically in motion, these means here consisting of a latch 177 that normally holds clutch 155 out by engaging pin 178 carried by rod 179 and thereby preventing spring 180 from actuating bell crank 181 that in turn controls the clutch. Latch 177 is on a rod 182 which, when pulled to the right in the drawings, is lifted by pin 183 thereby disengaging pin 178 and allowing spring 180 to act. Rod 182 is connected to bell crank 184 and from the latter extends operating rod 185 vertically down through the machine and is provided at its lower end with head 186. 187 denotes arms pivoted at 188 and normally urged upward by spring 189 and when free so to do these arms move upward against head 186 and thus throw in clutch 155. Normally, these arms are restrained from moving upward by means of bell cranks 190 that engage the web rolls and are connected to said arms by connection 191.

Normally, the parts are in the position shown in Fig. 4 and the device is idle, but when employed web roll 1 has been reduced in diameter to a sufficient extent (as in Fig. 5), its bell crank 190 falls down and an arm 187 strikes head 186 and clutch 155 is thrown in.

Under normal conditions member 104 and

its roll 105 will be in the position at the extreme right in Fig. 4, while, at the same time, member 102 and its rolls 103 and 103^a will be in the uppermost position. Assuming that the printing machine is running at printing speed and it is desired to change a web roll, web 37 is now passed over rolls 39, 40, 41, 101 and 103^a and up between jaws 108 and 109 which latter may at this time be separated as much as may be desired and the end of web 37 is placed in a gripper 123 or other web-secur ing device and has its end pasted. The accumulating devices are now started in operation thereby causing member 104 to move to the left and member 102 to move down. Meanwhile, we will assume that the printing machine remains at printing speed and that jaws 108 and 109 are still slightly separated. Member 104 and roll 105 now move to the left in the drawing at first slowly and then more rapidly until say an intermediate position of roll 105 is attained. At the same time, member 102 is moving downward, at first slowly and then more rapidly, until, say, an intermediate position of rolls 103 and 103^a is attained. During this action (from full to intermediate position) the printing machine will draw at first very little of the surplus of accumulating device 104 but will draw most of the required web from roll 1. As the accumulating devices speed up, however, the printing machine will draw more and more from the surplus of accumulating device 104 and less and less from roll 1 until finally, at the intermediate position, the printing machine can draw its entire supply from the surplus of 104 and nothing at all from roll 1. The web section between the jaws 108 and 109 is now standing still (or if desired may move slightly). At this time, owing to downward movement of member 102, rollers 114 and 115 act on cams 116 and 117 and close jaws 108 and 109 thereby pasting the two webs together. The jaws then separate and member 120 then severs web 2 by reason of the downward movement of cam 173, its pin 175 having been previously withdrawn by hand; pin 175 of member 121, however, remains in position and cam 173 therefore does not actuate said member 121. Considering now what happens to web 37, it will be understood that as soon as member 102 commences its downward movement, from its uppermost position, roll 103^a will commence to draw web 37, at first very slowly, and then more rapidly, until the intermediate position is reached when web 37 will attain full printing speed. The substitute roll 38 will therefore have been brought up to speed before pasting takes place; or, to put it differently, webs 2 and 37 will, of necessity, move at substantially the same speed. The sections of both webs between the first and second accumulating devices, may, however, be at rest, or substantially so, so that sections of both webs are sub-

stantially at a standstill at the moment they are joined together. The pasting now having taken place, the jaws separate. During the continued downward movement of rolls 5 103 and 103^a from the intermediate position to the lower position, their motion is gradually retarded as is also the movement of roll 105 from the intermediate position to the left-hand position. The result is that the 10 printing machine begins to move both web sections (the end of web 37 slipping out of the gripper 122 which latter may be opened mechanically) at first very slowly, and then more quickly until said lower and left-hand 15 position is reached, the speed of roll 38 remaining substantially constant. When the upward stroke of rolls 103 and 103^a and the right-hand stroke of roll 105 takes place, the web is running at full speed but the surplus 20 of the second accumulating device is being dissipated and the surplus of the first accumulating device is being created, one balancing the other. On the upward stroke, rolls 114 and 115 pass inside cams 116 and 117 25 so that no second closing of the jaws 108 and 109 takes place.

As soon as clutch 155 has been thrown in, arm 187 can be drawn down and a pin inserted in opening 192 thereby keeping it in 30 normal position, and when shaft 154 has made one revolution clutch 155 throws itself automatically out and latch 177 becomes again active to hold pin 178. Another roll is now substituted in place of roll 1 and pin 35 192 may now be withdrawn. Before the next roll change takes place, pin 175 of member 120 is placed in position and pin 175 of member 121 is removed.

In Fig. 6, a modification of the invention 40 is shown, the only difference being that rolls 103, 103^a and 105 are all carried by the same member 122, there being in this case a stationary roll 124 by means of which roll 105 forms its surplus, that is to say, the main 45 and auxiliary web surplus accumulating and dissipating devices are both carried by the same reciprocating member. Otherwise the action is the same as in the form of the invention first mentioned.

50 It will be seen from the foregoing description of the different forms of the invention, that one feature thereof resides in the method of accumulating a surplus in a web of flexible material to thereby start rotation of a web roll, such as the replenishing roll, while holding the leading end of the web stationary and attaching another web, such as the employed web, to the leading end of the first web and then dissipating the 55 surplus. In another aspect of the invention the method consists in accumulating a surplus in the employed web and dissipating it to slow down the speed of a portion of the web, accumulating another 60 surplus in the employed web in rear of the 65

first surplus, while the first surplus is being dissipated, and simultaneously therewith accumulating a surplus in the replenishing web while holding its leading end stationary, and attaching the two webs together, while 70 the first surplus is being dissipated and the second surplus is being accumulated, in a zone intermediate the points of dissipation and accumulation.

75 Looking at this invention from another angle, it will be understood from the foregoing that there is always a surplus present in the stretch of web between the web roll and the web pulling machine; and that it is the transfer of this surplus from one place 80 in the web to another that accomplishes the slowing down of the web. Thus, when the web surplus is transferred to the lower rolls 103 and 103^a, the stretch of web between rolls 103, 103^a and 105 is slowed down or stopped 85 and when the surplus is transferred to roll 105 the web stretch in question is speeded up.

90 It will also be understood that, while the cycle of the machine, during a roll change, has been described as beginning with a downward movement of rolls 103 and 103^a and ending with the completion of their upstroke, this has been done merely by way of example obviously the cycle could begin with 95 an upstroke of rolls 103 and 103^a and end with the completion of their down stroke; or, the roll change can take place on the down stroke of rolls 103 and 103^a and the upstroke can be made at any time thereafter, in which 100 case the cycle would be broken up, as it were, into several independent movements.

I claim:

1. The method of joining two webs of flexible material which consists in: accumulating 105 a surplus in a replenishing web to thereby start rotation of its web roll while holding the leading end of the web stationary, attaching an employed web to the leading end of the replenishing web, and then dissipating 110 the surplus by gradually speeding up the leading end of the replenishing web.

2. The method of joining two webs of flexible material which consists in: accumulating 115 a surplus in an employed web, dissipating said surplus to thereby slow down the speed of a portion of the web, accumulating another surplus in the employed web in rear of the first surplus while said first surplus is being dissipated, simultaneously therewith accumulating a surplus in a replenishing web 120 while holding its leading end stationary, and attaching the two webs together while the first surplus is being dissipated and the second surplus is being accumulated in a zone 125 intermediate the points of dissipation and accumulation.

3. The method of joining two webs of flexible material which consists in: accumulating 130 a surplus in an employed web, dissipating

said surplus to thereby slow down the speed of the web in rear of the surplus, starting up movement of a replenishing web roll while holding the leading end of the replenishing roll stationary, and attaching the slowed-down portion of the employed web to the leading end of the replenishing web.

5 4. A web-pulling machine, two sources of supply of web material, one an employed roll and another a replenishing roll, and means for changing from one web roll to another including two web surplus accumulating and dissipating devices, one main and the other auxiliary, acting oppositely on the web 10 so that when one is accumulating a surplus the other is dissipating another surplus and vice versa.

5 5. A web-pulling machine, two sources of supply of web material, one an employed roll 20 and another a replenishing roll, means for changing from one web roll to another including two web surplus accumulating and dissipating devices, one main and the other auxiliary, acting oppositely on the employed web 25 so that when one is accumulating a surplus the other is dissipating another surplus and vice versa, and opposed members to press together two webs from the two rolls while the main device is dissipating a surplus.

30 6. A web-pulling machine, two sources of supply of web material, one an employed roll and another a replenishing roll, means for changing from one web roll to another including two web surplus accumulating and dissipating devices, one main and the other auxiliary, acting oppositely on the employed web 35 so that when one is accumulating a surplus the other is dissipating another surplus and vice versa, and opposed members, to press together two webs from the two rolls, located intermediate the two web surplus accumulating and dissipating devices.

45 7. A web-pulling machine, two sources of supply of web material, one an employed roll and another a replenishing roll, means for clamping the leading end of the replenishing web, a web surplus accumulating and dissipating device to act on the employed web between the web-pulling machine and the 50 clamping means, and an auxiliary web surplus accumulating and dissipating device between the clamp and the sources of supply to act on both of the webs and timed to accumulate a surplus while the first device is dissipating a surplus and vice versa.

55 8. A web-pulling machine, two sources of supply of web material, one an employed roll and another a replenishing roll, means for clamping the leading end of the replenishing web, a web surplus accumulating and dissipating device to act on the employed web between the web-pulling machine and the clamping means, an auxiliary web surplus accumulating and dissipating device between the clamp and

the sources of supply to act on both of the webs 65 and timed to accumulate a surplus while the first device is dissipating a surplus and vice versa, and means for attaching the two webs together at a point intermediate the first and second devices.

70 9. A web-pulling machine, two sources of supply of web material, one an employed roll and another a replenishing roll, means for changing from one web roll to another including two web surplus accumulating and dissipating devices, one main and the other auxiliary, acting oppositely on the employed web so that when one is accumulating a surplus the other is dissipating another surplus and vice versa, opposed members to press together 80 two webs from the two rolls, and means for actuating said members from the auxiliary device.

85 10. A web-pulling machine, two sources of supply of web material, one an employed roll and another a replenishing roll, means for changing from one web roll to another including two web surplus accumulating and dissipating devices, one main and the other auxiliary, acting oppositely on the employed web 90 so that when one is accumulating a surplus the other is dissipating another surplus and vice versa, opposed members to press together two webs from the two rolls, severing means for the employed web, and means to actuate said severing means.

95 11. A web-pulling machine, two sources of supply of web material, one an employed roll and another a replenishing roll, means for changing from one web roll to another including two web surplus accumulating and dissipating devices, one main and the other auxiliary, acting oppositely on the employed web 100 so that when one is accumulating a surplus the other is dissipating another surplus and vice versa, opposed members to press together two webs from the two rolls, severing means to sever the employed web, and means to actuate said severing means by movement of the auxiliary device.

105 12. A web-pulling machine, two sources of supply of web material, one an employed roll and another a replenishing roll, means for changing from one web roll to another including two web surplus accumulating and dissipating devices, one main and the other auxiliary, acting oppositely on the employed web 115 so that when one is accumulating a surplus the other is dissipating another surplus and vice versa, opposed members to press together two webs from the two rolls, severing means to sever the employed web, and means to actuate the opposed members and the severing means by movement of the auxiliary device.

120 13. Web-attaching means including: two opposed arms pivotally supported, and means for moving said arms toward and away from each other including a reciprocating mem-

ber and complementary cam means on the arms and member actuated by the movement of the reciprocating member.

14. Web-attaching means including: two opposed arms pivotally supported, and means for moving said arms toward and away from each other including a reciprocating member and complementary cam means between the reciprocating member and arms to move the arms toward each other during the stroke of the reciprocating member in one direction and to separate them during the stroke of the reciprocating member in the other direction.

15. Web-attaching means including: two opposed arms pivotally supported, and means for moving said arms toward and away from each other including a reciprocating web surplus accumulating and dissipating device, and complementary cam means between said device and the arms actuated by the movement of the reciprocating device.

16. Web-replenishing means including: a surplus accumulating and dissipating device normally inactive, actuating means for said device, a one-revolution clutch to connect and disconnect the actuating means and the dissipating device, means for normally holding such clutch out, a source of supply including a web roll, and means for throwing in the clutch when the diameter of the web roll has been diminished to a certain extent.

17. Web-replenishing means including: a web surplus accumulating and dissipating device normally inactive, a source of supply including a web roll, actuating means to drive said device, a one-revolution clutch to connect and disconnect the actuating means and the

device, means for normally holding the clutch out, and means controlled by the diameter of the roll to throw the clutch in. 40

18. Web-replenishing means including: a web surplus accumulating and dissipating device having a back-and-forth movement, a rotating crank to actuate the device, making one revolution to each back-and-forth movement of the device, a connection between the crank and the device, actuating means to drive the crank and normally disconnected therefrom, a one-revolution clutch to connect the actuating means and the crank, means for normally holding the clutch out, a source of supply of material including a web roll, and means controlled by the diameter of the web roll to throw in the clutch. 45 50

19. The method of joining two webs of flexible material which consists in transferring a surplus from one point in a web to another point therein to thereby slow down the speed of a portion of the web intermediate the two points, and attaching a second web to the slowed-down portion of the first web. 55

20. The method of joining two webs of flexible material which consists in transferring a surplus from one point in a web to another point therein to thereby slow down the speed of a portion of the web intermediate the two points, attaching a second web to the slowed-down portion of the first web, and transferring the surplus in the web from the other point back to the first point. 60 65 70

Signed at New York in the county of New York, and State of New York, this 20th day of October, 1925.

CARL E. DRANGE.
